US00D602029S

(12) United States Design Patent
Lloyd et al.

(10) Patent No.: US D602,029 S
(45) Date of Patent: * Oct. 13, 2009

(54) GRAPHICAL USER INTERFACE FOR DISPLAYING MULTIMEDIA CONTENT FOR A DISPLAY SCREEN

(75) Inventors: Andrew J. Lloyd, St. Albans (GB);
Matia Wagabaza, Santa Monica, CA
(US)

(73) Assignee: Yahoo! Inc., Sunnyvale, CA (US)

() Term: 14 Years

(21) Appl. No.: 29/323,780

(22) Filed: Aug. 29, 2008

(51) LOC (9) Cl. 32-00

(52) U.S. Cl. D14/485

(58) Field of Classification Search D14/485-495;
705/28; 715/700, 703, 709, 712, 716, 719,
715/720, 721, 727, 728, 752, 753, 757, 768,
715/771, 772, 777, 782, 808, 809, 810, 812,
715/819, 820, 821, 825, 833, 834, 835, 836,
715/837, 838, 839, 840, 841, 842, 843, 846,
715/848, 849, 850, 851, 852, 856, 861, 864,
715/961, 962, 963, 970, 977

See application file for complete search history.

(57) CLAIM

The ornamental design for a graphical user interface for displaying multimedia content for a display screen, as shown and described.

DESCRIPTION

The FIGURE is a front view of a graphical user interface for displaying multimedia content for a display screen.

The broken lines showing a display screen forms no part of the claimed design. The text and images shown in broken lines forms no part of the claimed design.

1 Claim, 1 Drawing Sheet
